UNITED STATES PATENT OFFICE.

THOMAS G. AULTMAN, OF FAIRMONT, WEST VIRGINIA, ASSIGNOR TO
JOSEPH A. JEFFREY, OF COLUMBUS, OHIO.

CHAIN AND CUTTER-CARRYING DEVICE.

SPECIFICATION forming part of Letters Patent No. 787,551, dated April 18, 1905.

Application filed June 28, 1902. Serial No. 113,664.

To all whom it may concern:

Be it known that I, THOMAS G. AULTMAN, a citizen of the United States, residing at Fairmont, in the county of Marion and State of West Virginia, have invented certain new and useful Improvements in Chains and Cutter-Carrier Devices, of which the following is a specification, reference being had therein to the accompanying drawings.

This invention relates to improvements in chains and cutter-carrier devices connected therewith which are used in machines for mining coal and similar mechanisms.

The object is to provide a chain and cutter-carrier which shall have the greatest possible strength with economy of metal and cost of manufacture and one to which the cutters can be fitted and wherein they can be adjusted with greater convenience than has been incident to the devices for these purposes that have been heretofore employed.

Figure 1 shows in plan view one of the carrier-frames of a mining-machine adapted to have applied thereto a chain and cutter-holder embodying my improvements. Fig. 2 is a plan view of a section of the cutter-chain detached and on an enlarged scale. Fig. 3 is a cross-section of the chain in Fig. 2. Fig. 4 is an end view, and Fig. 5 a plan view, of a cutter-carrying link. Fig. 6 is an end view, Fig. 7 a plan view, and Fig. 8 a face view, of a cutter-carrying link having the cutter-sockets arranged somewhat differently from those in Figs. 4 and 5. Fig. 9 is an end view of one of the links connecting the cutter-carrying links.

In the drawings, A indicates a portion of the chain-supporting frame or cutter-frame, such as is now commonly used in coal-mining machines; but it will be understood that the present improvements are not restricted to any particular form of mining-machine so far as concerns the carriage, the bed-frame, gearing, engine, and other parts supplemental to the chain. In these machines it is customary to have a chain-guide around more or less of the chain-frame A, which guide is formed with lips or flanges a, adapted to hold the chain-links in proper lines, as will be more fully described below.

The chain which I have illustrated is built up of the links B B' B², each articulated to those adjacent. The links B are each formed of two side bars b b, each side bar having at each end an inwardly-turned thimble or sleeve b'. The thimbles furnish the draft-receiving parts and also receive the binding and fastening pins or pintles to be described. The links B' and B² are the cutter-carrying parts and are approximately similar to each other except for certain differences in detail, which will be described below.

Referring to the link B', it will be seen that it is composed of two parts C and C', the part at C being in line with the links B and the part C' extending laterally outward therefrom. The part C is formed with a shank portion or body portion c, at the ends of which are the coupling-eyes c' and between which are the guide projections c². The coupling parts c' have apertures c³, within which are fitted snugly the thimbles or sleeves b'. After the side bars b of the link B are fitted to the part C, with their sleeves b' inserted oppositely into an aperture c³, they (the side bars b) and the link B' are fastened together articulately by means of the pin F, which at its ends is upset or headed or provided with suitable retaining devices.

The laterally-projecting part of the link B' is formed with a neck portion D' and the expanded or head portion D. Adjacent to the neck part and between the projections c² and the outer head part D there are open ways or groove-like passages d', in which are fitted the aforesaid flange-lips a of the frame-guide, which act to prevent the chain from either moving outward or inward beyond the desired lines, but which have sufficient clearance to allow the links to move rapidly and smoothly around their path. The head part D is expanded or flared downward and upward, as shown at d², and through the metal thus provided and through the neck part D' and the shank at c there are formed cutter-receiving apertures E E', one inclined downward and the other inclined upward.

At d³ d³ there are bosses or enlargements of the metal on the front side of the cutter-

- head, and each of these is provided with an aperture transverse to the cutter-apertures E E', as shown at d⁴. These apertures are threaded and adapted to receive set-screws G. 5 The inner ends of the set-screws bear, respectively, against the shanks or stocks h of the cutters H H' and fasten them firmly in place after adjustment.
- The cutter-link at B² is, as aforesaid, substantially similar to that at B' just described, the difference being that the head part D is not expanded so much and the cutter-sockets E E' are at lesser inclinations to the horizontal and the set-screws are arranged one in 10 front of the head and one in the rear of the same.
- A cutter-chain can be built up by connecting together the links B B' B² under such arrangement as seems best for the purpose to 15 be accomplished—that is to say, it may be formed of a series of sections, each section having a link B', a link B, a link B², and another link B, in which case throughout the entire chain there will be equal numbers of 20 the several links, or there may be a greater number of the links B' in the chain and a correspondingly lesser number of the links B², or vice versa. It will be seen that with a 25 chain of this character provision is made for attacking the coal or other material along four horizontal lines—an extreme upper line, an extreme lower line, and two intermediate ones. It will be also seen that the cutters are all alike and interchangeable, no special shaping 30 being required with those of one line in comparison with those of another line. The cutters can be readily adjusted and can be easily withdrawn for sharpening or to permit the substituting of others. The articulating 35 parts are so joined together that all cutting and wearing of the cross-pin is avoided, the sleeves b' being so arranged as to not only take all of the draft in moving and applying power to the chain, but also take all of the 40 wear incident to the articulating movements, and as these sleeves are of relatively large diameter this wear is safely distributed over large surfaces and the durability and strength of the chain are greatly enhanced.
- 45 50 What I claim is—
1. In a cutting mechanism for mining-machines and similar purposes, a cutter-chain having a series of cutter-carrying links, each formed with a shank on the draft-line of the chain, and with a laterally-extending cutter-supporting body having a head, as at D, with two cutter-sockets inclined to the plane of the chain and extending continuously from the outer face of the head D through the shank 55 60 part of the link, and a groove-like passage d' between said head and the shank adapted to

receive a guiding-flange for said chain, substantially as set forth.

2. In a cutting mechanism for mining-machines and similar purposes, a cutter-chain 65 having a series of cutter-carrying links each formed with a shank situated on the draft-line, and a laterally-extending cutter-supporting body formed with a head D having two independent cutter-sockets in planes transverse of the chain and arranged to hold one cutter in advance of the other, each socket extending through said head and shank, substantially as set forth.

3. In a cutting mechanism for mining-machines and similar purposes, a cutter-chain having a series of cutter-carrying links each formed with a shank situated on the draft-line, and a laterally-extending cutter-supporting body formed with a head D having two 80 independent cutter-sockets in planes transverse of the chain and arranged to hold one cutter in advance of the other, and means for clamping the cutters in said sockets independently of each other, each socket extending 85 longitudinally through said head-shank, substantially as set forth.

4. In a cutting mechanism for mining-machines and similar purposes, a cutter-chain having a series of cutter-carrying links, each 90 formed with a shank on the draft-line of the chain and with a laterally-extending cutter-supporting body having a head as at D with two independent cutter-sockets arranged at an angle to each other and adapted to hold one 95 bit in advance of the other and in different horizontal planes, said sockets extending continuously from the outer face of the head D through the shank part of the link, substantially as set forth.

5. In a cutting mechanism for mining-machines and similar purposes, a cutter-chain having a series of cutter-carrying links each formed with a shank on the draft-line of the chain with a laterally-extending cutter-supporting body having a neck as at D' with 105 grooves d' at either side thereof adapted to receive the guide-flange for the chain on the cutter-carriage and a head as at D with two cutter-sockets extending continuously from 110 the face of the head through the neck part and through the shank part of the link, in combination with cutters inserted in said sockets, and set-screws for fastening the cutters in position independently of each other, substantially as set forth.

In testimony whereof I affix my signature in presence of two witnesses.

THOMAS G. AULTMAN.
